UNITED STATES PATENT OFFICE.

LAWRENCE L. NEEBE, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

AIR-DRUM SUPPORT FOR LOCOMOTIVES.

Application filed November 28, 1925. Serial No. 72,004.

One object of my invention is to provide means for supporting the air drums independently of the locomotive boiler, so as to relieve the boiler from strain at the studs which usually secure the supporting brackets of the air drums to the boiler.

A further object of the invention is to utilize the waist-sheets of the locomotives for supporting the air drums.

10 In the accompanying drawing:

Fig. 1 is a side elevation of a portion of a locomotive;

Fig. 2 is a transverse section of a locomotive taken on the line 2—2, Fig. 1, showing the waist-sheets and the air drums carried independently of the boiler; and

Fig. 3 is a perspective view of the air drum supports which are secured to the waist-sheet.

20 1, 1 are the side frames of a locomotive.

2, 2 are the waist-sheets which are secured to cross members 3 of the frame in the ordinary manner. 4 is the locomotive boiler. 5 is a curved angle-iron which forms

25 a saddle for the support of the boiler. This saddle may be secured by rivets or studs to the boiler, and to the waist-sheet by a series of bolts as shown.

The waist-sheet has extensions 6 at each 30 side which form brackets to which the air drum supports 7 are attached by a series of bolts 8. Each bracket has a curved seat 9 for an air drum 10, and straps 11 extend over the air drum. The ends of these straps are

threaded and passed through openings 12 35 in the supports, and nuts 13 are mounted on the threaded portions of the straps so that on turning the nuts, the straps draw the drums firmly onto the seat.

It will be noted that the air drums or 40 their supports are not attached to the boiler, so that any vibration of the air drum will not affect the boiler.

While I have shown an air drum on each side of the boiler, in some instances only 45 an air drum may be mounted on one side, without departing from the essential features of the invention.

I claim:

1. The combination in a locomotive boiler; a waist-sheet supporting the boiler; and 50 an air drum carried by the waist-sheet independently of the boiler.

2. The combination in a locomotive boiler; a waist-sheet supporting the boiler; an 55 extension on the waist-sheet forming a bracket; a support rigidly secured to the bracket; and an air drum mounted on the support.

3. The combination in a locomotive 60 frame; a waist-sheet; a boiler secured to the waist-sheet, said waist-sheet having a bracket at each side; a support secured to each bracket, said support having a seat; an air drum mounted on the seat; and 65 straps securing the air drums to the supports.

LAWRENCE L. NEEBE.
